DESIGN FOR A LIPSTICK CASE

Maximilian C. Meyer, Brooklyn, N. Y.

Application March 19, 1941, Serial No. 99,699

Term of patent 7 years

To all whom it may concern:

Be it known that I, Maximilian C. Meyer, a citizen of the United States, residing at Brooklyn, in the county of Kings and State of New York, have invented a new, original, and ornamental Design for Lipstick Case, of which the following is a specification, reference being had to the accompanying drawing forming a part thereof.

I claim:

The ornamental design for a lipstick case, as shown.

MAXIMILIAN C. MEYER.
